UNITED STATES PATENT OFFICE.

JACOB GREULOCHE, JR., OF CLEVELAND, OHIO.

CAN FAUCET AND FILLER.

SPECIFICATION forming part of Letters Patent No. 341,476, dated May 11, 1886.

Application filed October 12, 1885. Serial No. 179,579. (No model.)

To all whom it may concern:

Be it known that I, JACOB GREULOCHE, Jr., of Cleveland, in the county of Cuyahoga and State of Ohio, have invented a certain new 5 and Improved Can Faucet and Filler; and I do hereby declare that the following is a full, clear, and complete description thereof, reference being had to the accompanying drawings.

The combined can faucet and filler above alluded to is especially intended for oil-cans, although it may be applied to other vessels for discharging therefrom their liquid contents.

The accompanying drawings will be referred to in the course of the following specification 15 and make a part of the same, in which—

Figure 1 represents a side view of the invention applied to a can. Fig. 2 is a transverse vertical section through line *x x*. Fig. 3 is a plan view.

Like letters of reference refer to like parts 20 in the several views.

The faucet above mentioned consists of a tubular stem, A, provided with a male thread, as shown in Fig. 1. The lower end of said 25 tubular stem terminates in a funnel-shaped enlargement or mouth, B, Fig. 2, whereas the upper end of the stem is closed and provided with spout C, in open relation with the bore of the stem.

b is a vent-hole, and D is a collar and an 30 integral part of the tubular stem. On said stem is screwed a nut, E, forming an integral part of the cap F, substantially as shown in the drawings.

G is a packing surrounding and adapted to 35 fit on over the exterior surface of the mouth B of the tubular stem above alluded to, and as shown in Fig. 2. Said packing may be of rubber, leather, or of any suitable material other 40 than the material mentioned.

H, Fig. 2, is a plug-valve, fitted closely to 45 the inside of the mouth B of the stem. Said valve is opened and closed by the rod I, the upper end of which is screwed into and through the closed end of the tubular stem A, and the external end of the said rod is provided with a thumb-piece, J, by which the rod is worked for the purpose of opening and closing the valve H, above mentioned.

K is a lug fixed to the side of the nut, the 50 use of which will presently be shown.

When the can is to be filled, the faucet may be removed and afterward replaced.

Having described the construction of the 55 said invention, the practical use of the same is as follows: As shown in the drawings, L represents a portion of an oil-can, of which M is the top. In said top of the can is made an opening sufficiently large to allow the flaring 60 mouth B of the tubular stem to pass through to the interior of the can, and also to allow the packing G to be crowded in around it by the collar D on pushing down therein the flaring mouth B and the packing when inserted in the can, as above described. The packing 65 is then drawn upward and expanded, so as to fill the opening in the can by screwing down the nut E (which forms a part of the cap F, as seen in Fig. 2,) until the edge of the cap F comes down upon the top of the can. A continual 70 turning of the nut draws upward the flaring mouth B of the stem, thereby expanding the packing and forcing it against the sides of the opening in the can, as seen in Fig. 2, thus forming an oil-tight joint, which is covered by the cap F, substantially as shown in Fig. 2, which represents the faucet attached to the can, as above described, and closed by the valve H.

To pour out the contents of the can, the valve 80 H is opened by screwing downward the valve-rod I, by the thumb-piece J, as indicated by the dotted lines *a*, when, on tipping the can, the oil will flow from the can through the tubular stem and out of the spout C.

The can, when empty, may be again filled by screwing upward the nut-cap E so far as to allow the flaring mouth B of the tubular stem to be pushed down into the can so far as to allow the tubular stem to be tipped over to 90 one side, which causes the packing to be drawn out of one side of the opening of the can, which will admit of sufficient space for the admission of oil; or the said faucet can thus be taken out by tipping it over to one side to free the 95 packing, leaving the opening into the can clear for filling it, which when done the faucet is again attached, as above described.

By means of a suitable wrench arranged to engage the lug K the nut F may be tightly screwed down on the can, thus securing the packing in place in the can-opening, as before described.

In place of using a wrench and the lug K, the nut F is or may be corrugated, as seen at c, Fig. 1, which will allow of the nut being held with sufficient force to be screwed down, and to secure the packing in position to make a tight joint without the said wrench.

What I claim as my invention, and desire to secure by Letters Patent, is—

For oil-cans, a faucet consisting of a tubular

stem provided with a male thread and a 15 spout, C, collar, flaring mouth, and packing covering the external surface of said mouth, in combination with the valve H and stem, cap F, having the nut E, and can, constructed substantially as described, for the purpose set forth.

In testimony whereof I affix my signature in presence of two witnesses.

JACOB GREULOCHE, JR.
